(57) **CLAIM**

The ornamental design for interconnectable furniture, as shown and described.

DESCRIPTION

FIG. 1 is a top perspective view of the interconnectable furniture embodiment;

FIG. 2 is a top view of the interconnectable furniture design; FIG. 3 is a bottom view of the interconnectable furniture design;

FIG. 4 is a front view of the interconnectable furniture design; FIG. 5 is a rear view of the interconnectable furniture design; FIG. 6 is a left side view of the interconnectable furniture design;

FIG. 7 is a right side of the interconnectable furniture design; FIG. 8 is a top plan view showing the interconnectable furniture design in a configuration of three with all but one in broken lines for environmental purposes only and forming no part of the claimed design;

FIG. 9 is a top plan view showing the interconnectable furniture design in a configuration of four with all but one in broken lines for environmental purposes only and forming no part of the claimed design;

FIG. 10 is a top plan view showing the interconnectable furniture design in a configuration of five with all but one in broken lines for environmental purposes only and forming no part of the claimed design; and,

FIG. 11 is a top plan view showing the interconnectable furniture design in a configuration of ten with all but one in broken lines for environmental purposes only and forming no part of the claimed design.

Broken lines in the figures are used to depict structure that is not part of the claimed design, but is considered necessary to show the environment in which the design is associated.
